BOX FOR BALANCE WHEELS

Kurt Zehntner, Liestal, Switzerland, assignor to Renata
S.A., Frenkendorf, Switzerland

Application November 6, 1957, Serial No. 48,353

Term of patent 7 years

(Cl. D58—11)

Figure 1 is a side view of a box for balance wheels embodying my new design in a closed position;

Figure 2 is a top plan view thereof;

Figure 3 is a bottom plan view thereof;

Figure 4 is a perspective view thereof, showing the cover removed from the box;

Figure 5 is a section along the line 5—5 of Figure 3.

I claim:

The ornamental design for a box for balance wheels as shown:
